UNITED STATES PATENT OFFICE.

CLARKE P. POND, OF PHILADELPHIA, PENNSYLVANIA.

WINDOW-OPERATING DEVICE.

1,228,242.

Specification of Letters Patent. Patented May 29, 1917.

Application filed June 1, 1916. Serial No. 101,073.

To all whom it may concern:

Be it known that I, CLARKE P. POND, a citizen of the United States, residing in Philadelphia, Pennsylvania, have invented 5 certain Improvements in Window-Operating Devices, of which the following is a specification.

One object of my invention is to provide a comparatively simple and substantial 10 mechanism for swinging one or a series of pivoted sashes or ventilators on their supports to open or close them, the arrangement of the parts being such as will allow of the accurate and inexpensive construction and 15 erection of such mechanism as well as its convenient operation.

The invention also contemplates a novel arrangement of supporting structure, levers, and connections, assembled to form mechanism 20 for opening or closing one or more sashes, whereby the force applied to move the sash is varied in a definite manner depending upon its position.

These objects and other advantageous 25 ends I secure as hereinafter set forth, reference being had to the accompanying drawings, in which,

Figure 1 is an elevation of two sets of 30 sashes or ventilators equipped with my invention;

Figs. 2 and 3 are respectively a plan, partly in section, and an end elevation, of the parts illustrated in Fig. 1;

Figs. 4 and 5 are respectively a plan and 35 a front elevation illustrating the detail construction of my operating mechanism;

Figs. 6 and 7 are respectively a plan and an elevation of a slightly modified form of 40 the invention;

Fig. 8 is a perspective view of one of the 45 levers forming part of the device shown in Figs. 6 and 7;

Fig. 9 is an elevation, partly in section, of the lever-connecting link employed in that 50 form of my invention shown in Figs. 4 and 5; and

Figs. 10 and 11 are horizontal sections on the line 10—10 and 11—11, respectively, 55 Fig. 9.

In the above drawings 1 and 2 represent 60 two sets of sashes mounted one above the other and supported to swing on pivots 3

of which those belonging to any one set of sashes are placed at the centers of the sides or ends thereof.

Each set of sashes, as shown in Fig. 3, has 65 projecting from it, adjacent its pivot, a plate or casting 4 constituting an operating arm and the arm at each side of the sash 1 is connected to the corresponding arm of the sash 2 below it by a bar 5 so that the two sashes naturally swing together.

For opening and closing the sashes I provide 70 a lever mechanism preferably mounted on a supporting frame 6 having approximately the form of two members extending at right-angles to each other and conveniently attached to the window frame between and to one side of the two sashes by screws or any other suitable means, so that 75 its members lie in a plane parallel to that of the sash frame.

The vertically extending member of said frame 6 has pivoted to its upper end a lever 80 consisting of two arms 7 and 8 parallel to each other and made in a U-shaped form; the pivot being horizontal. The latter of these arms is pivotally connected to the adjacent operating bar 5 of the sash while the second is connected through a link 10 with 85 one arm 11 of a second lever pivoted to the outer extremity of the second member of the frame 6 so that it is free to swing in a substantially vertical plane.

As shown in Fig. 1, there is a pair of 90 levers and their connecting link carried on a frame 6 at each side of the sashes 1 and 2, and for actuating this mechanism I provide suitable means such as that shown in my Patent No. 886,851, dated May 5th, 1908.

In the present instance I have illustrated 95 two horizontally extending parallel rods or bars 13 and 14 which may be moved in opposite directions and to one of these is pivotally connected the second arm 12 of the second lever which swings in a horizontal plane adjacent the left-hand one of the bars 5. Similarly an arm 12 of the horizontal lever at the right-hand end of the sashes is pivoted to the rod or bar 14, any suitable 100 form of clamp being provided on the two operating bars and the lever arms being pivoted to said clamps. The connections between the arms 7 and 11 and the link 10 are

illustrated in Figs. 9 to 11 inclusive, from which it will be seen that there are universal joints interposed between these parts. In designing the latter the two ends of the link 10 are made forked and the branches of each fork are connected by a suitable pivot pin 15 which has fixed to its central portion a spherical bearing structure 16. In the present case the adjacent extremity 17 of the lever arm is turned at right-angles to the body thereof and is perforated to receive this ball-bearing.

Similarly the pivot 18 at the opposite end of the link 10 carries a ball bearing 19 fitted into a perforation in the arm 7 of the vertically moving lever. With this arrangement of parts there is no binding between the link and the two levers when these are moved in any of their possible positions and it is noted that the turned-up end 17 of the lever 11-12 extends in a plane inclined to the center-line of the arm 11, as shown in Fig. 10.

Under operating conditions the simultaneous movement of the rods 13 and 14 in opposite directions causes a simultaneous swinging of the levers 11-12 on their pivots and if the sash be closed, the levers 7-8 are both swung downwardly on their pivots by power transmitted from the levers 11-12 through the links 10. As a consequence, there is a downward force exerted on the projecting operating arms 4 of both sets of sashes and these latter are caused to swing on their pivots from their closed to their open position.

With this arrangement of parts the greatest leverage or opening force occurs when the sashes are closed or in contact with the window frames, the movement being relatively slow but powerful and decreasing in force as the sashes are opened. In some cases, however, I may construct the operating mechanism as shown in Figs. 6, 7 and 8, in which case the angle frame 6^a has pivoted to the extremity of one of its arms a horizontally swinging lever 11^a-12^a. The arm 11^a of this lever is connected through a link 10^a with one arm 7^a of the vertically swinging lever whose second arm extends preferably at an acute angle to said first arm. As before, the link is connected to two levers through ball joints and it is noted that as the lever 7-8 is moved from the position shown in full lines to that shown in dot, the pull or force exerted upon its arm 8^a increases. This particular form of the invention is designed for the operation of sashes which are pivoted or hinged to their supports adjacent their upper ends so that it meets the increase

of load resulting from the opening of the sashes, with an increase of leverage.

I claim;—

1. The combination in a sash operating device of a supporting frame consisting of two members substantially at right-angles to each other; a lever mounted on one member of the frame and movable on a horizontal axis; and a second lever mounted on the other frame member and free to swing on a vertical axis; with means for operatively connecting said levers. 65

2. The combination in a sash operating device of a supporting frame consisting of two bars extending substantially at right-angles to each other; a lever pivoted to one member adjacent the free end thereof and movable on a horizontal axis; a second lever pivoted adjacent the free end of the other frame member and movable on a vertical axis; with means for operatively connecting said levers. 75 80

3. The combination of a pivoted sash; a lever having an arm connected thereto and free to move on an axis parallel to the sash pivot; a second lever pivoted to move on an axis at right angles to that of the first lever and having an arm connected to a second arm of the first lever; with an operating member movable in either of two directions 85 90 and connected to the second arm of the second lever.

4. The combination of a plurality of sashes; a bar connecting said sashes; a lever pivoted to swing on a horizontal axis and having an arm connected to said bar; a second lever pivoted to swing on a vertical axis; a link connecting the second arm of the first lever with one arm of the second lever; a power actuated member movable in a horizontal line; and means for connecting said member with the second arm of the second lever. 95 100

5. The combination of sash frame; a sash pivoted therein; a frame including two members at right-angles to each other and mounted on the sash frame adjacent two sides of the sash; a lever mounted on said one of said members and free to swing on a horizontal axis; means for connecting one arm of said lever to the sash; a second lever pivoted to the second member of the frame and free to swing on a vertical axis; a link connecting the second arm of the first lever with an arm of the second lever; a power 115 actuated operating lever mounted to move adjacent the sash; and means for connecting said member with the second arm of the second lever. 105 110
